His Attorney.

UNITED STATES PATENT OFFICE

2,234,713

REFRIGERANT EVAPORATOR

Christian Steenstrup, Schenectady, N. Y., assignor to General Electric Company, a corporation of New York

Original application December 1, 1937, Serial No. 177,495. Divided and this application July 21, 1939, Serial No. 285,702

6 Claims. (Cl. 62—126)

My invention relates to refrigerant evaporators and more particularly to evaporators of the flooded type for household refrigerating machines and having large surface areas adapted to be operated at relatively high temperatures.

It is frequently desirable to maintain the surface of an evaporator for cooling a refrigerating compartment at relatively high temperatures so that the temperature differential between the cabinet air and the evaporator is small and temperatures near the freezing point of water may be maintained by an evaporator operating at a temperature above freezing. Evaporators of this type are useful for maintaining the air in refrigerated compartments at high relative humidity since the removal of moisture from the air by the continual formation of frost on the evaporator surface is avoided.

Accordingly, it is an object of my invention to provide a refrigerant evaporator of the flooded type having a large surface area relative to the area in direct contact with refrigerant and an improved arrangement for circulating refrigerant therein.

Another object of my invention is to provide a refrigerant evaporator having an improved arrangement for circulating refrigerant and which is inexpensive to manufacture and may readily be constructed of sheet metal.

Further objects and advantages of my invention will become apparent as the following description proceeds, and the features of novelty which characterize my invention will be pointed out with particularity in the claims annexed to and forming a part of this specification.

For a better understanding of my invention, reference may be had to the accompanying drawing in which Fig. 1 is a front elevation of the upper portion of a household refrigerating machine having an evaporator embodying my invention; Fig. 2 is an enlarged perspective view of the evaporator shown in Fig. 1; Fig. 3 is a sectional view on the line 3—3 of Fig. 2; and Fig. 4 is a view of the evaporator sheets in the flat prior to bending to form the side walls of the evaporator.

Referring now to the drawing, in Fig. 1 I have shown a refrigerating machine including a cabinet 10 having a food compartment 11 normally closed by a door (not shown) and a cooling unit 12 arranged within the compartment 11. A condensing unit comprising a closed casing 13, within which is arranged a motor and a compressor, and a condenser 14 having a refrigerant conduit 15 maintained on a removable top 16 of the cab-

inet 10. During the operation of the refrigerating machine, gaseous refrigerant is compressed by the compressor within the casing 13 and discharged into the conduit 15 where it is cooled and liquefied by the natural circulation of air over the conduit. The liquid refrigerant flowing through a connection 17 into a liquid receiver or float valve chamber 18. When a predetermined quantity of liquid refrigerant has collected in the chamber 18, a float therein rises and the liquid refrigerant flows through a conduit or inlet connection 19 to the cooling unit 12. The liquid refrigerant within the cooling unit 12 is vaporized by the absorption of heat from the air within the compartment 11 and from articles placed within the cooling unit 12. The vaporized refrigerant is withdrawn through a suction line 20 and returned to the casing 13. The refrigerating machine is provided with a control mechanism 21 having a thermostatic element 22 secured adjacent the upper portion of the cooling unit 12, the motor within the casing 13 being started and stopped by the control mechanism 21 in response to the temperature of the cooling unit as determined by the thermostatic element 22. The refrigerating machine thereby maintains the surface of the cooling unit 12 within a predetermined range of temperatures. The temperature range may be selected to maintain the evaporator surface always above freezing or it may be selected so that the temperature rises above freezing during each cycle and thus prevents the formation of any substantial quantity of frost, the latter method of operation being known as the "defrosting cycle."

Referring now to Figs. 2 and 3, the cooling unit 12 comprises a housing formed of inner and outer complementary metal sheets 23 and 24 respectively, welded together face to face and formed to provide three vertical walls forming the sides and back wall of the cooling unit. Flanges 25, 26 and 27 at the tops of the walls are provided to support the unit within the refrigerator cabinet in such manner as to hold the top of the unit against the underside of the top wall of the compartment 11. The bottom side of the cooling unit is closed by a wall or partition 28 and a partition comprising two walls 29 and 30 spaced apart to provide a dead air space may be provided to separate the housing into a plurality of compartments. As shown in Fig. 1, doors 31 and 32 have been provided to close the top and bottom compartments respectively. It is, therefore, not necessary to open the entire cooling chamber in order to gain access to a part thereof.

In order to circulate refrigerant through the side walls of the housing, I provide headers 33, 34 and 35 formed by complementary indentations in the inner and outer sheets 23 and 24 near the tops of the vertical walls of the evaporator. The headers 33, 34 and 35 during normal operation of the refrigerating machine are maintained about half filled with liquid refrigerant to maintain the evaporator passages flooded and are connected above the normal liquid level by passages 36 and below the normal liquid level by passages 37 to equalize the pressures and liquid levels of the several headers. In order to circulate liquid refrigerant in the walls of the evaporator, I provide a plurality of passages communicating with the several headers. The arrangement of the circulating passages is clearly shown in Fig. 4 which represents the sheets 23 and 24 in the flat before they are bent to form the walls of the evaporator. The headers 33, 34 and 35 and also the passages 36 and 37 are formed by indentations in both sheets. A plurality of vertical or upright passages 38 and 39 are formed in the outer sheet 24, each of the headers having a passage 38 communicating with the left end thereof, as shown in Fig. 4, and a passage 39 with the right end thereof. Each of the headers is thereby provided with a pair of depending passages. These pairs of passages are connected by a plurality of transverse passages 40 formed in the inner sheet 33. All of the passages 40 are parallel to each other but diverge slightly from the center line of the headers 33, 34 and 35 so that the ends of the passages 40 communicating with the vertical passages 38 are higher than the ends of the passages 40 communicating with the vertical passages 39. The total area of the refrigerant passages may comprise a relatively small portion of the area of the evaporator surface, as illustrated.

In order to supply liquid refrigerant to the passages of the evaporator, I provide a manifold 41 arranged in the sheet 24 parallel to the passages 40. One end of the manifold is connected to the liquid line 19 to receive liquid refrigerant, and injector ducts 42 are provided to conduct the refrigerant from the manifold into the lower ends of the passages 38. The liquid refrigerant passes through the ducts 42 and is directed upwardly into the passages 38. Since the passages 40 slant upwardly toward the passages 38 in each wall of the evaporator, there is a tendency for liquid refrigerant vaporized in the passages 40 to flow into the passages 38 and thereby produce some natural circulation of liquid refrigerant toward the passages 38 and into the headers. The natural circulation is effective when refrigerant is not being supplied to the evaporator, and positive circulation in the same direction is produced by the injector action of the ducts 42 when refrigerant is being supplied to the evaporator. The positive action of the injector ducts produces a rapid circulation of refrigerant through the passages 40 from the passages 39 to the passages 38. The refrigerant flows upwardly into the headers 33, 34 and 35 where the vaporized refrigerant is separated from the liquid refrigerant and a portion of the liquid refrigerant is returned to the passages 40 downwardly through the passages 39. Any gaseous refrigerant collecting in the headers is withdrawn through the suction line 20 which has been shown connected to the middle header 34, it being evident that vapor from the headers 33 and 35 is free to flow to the header 34 through the passages 36.

The several passages and the headers in the sheets 23 and 24 are formed while the sheets are flat. The sheets are then secured together by welding or brazing or in any other suitable manner around their edges and between the indentations and are then bent to form the three-sided housing as shown. It will be evident that since the passages 40 below the several headers are arranged in alignment and on the opposite side of the structure from the upright passages 38 and 39, the sheets 23 and 24 may be secured together by line welds formed along the sides of the passages 40 by a welding wheel which may traverse three walls of the evaporator without being lifted from the sheet 23. Furthermore, the inner sheet 23 has no vertical indentations which would interfere with the partition walls 29 and 30 and would require that the partitions be cut to conform to irregularities in the wall 23. Furthermore, a plurality of straight fins 43 may be secured on the outer wall 24 of the evaporator as shown in Fig. 2, without interference requiring cuts or notches to make them conform to the refrigerant passages.

If it is desired to provide capacity for freezing ice within the evaporator 12, a second evaporator or freezing shelf may be arranged within the housing as described and claimed in my copending application, Serial No. 177,495, filed December 1, 1937, of which this case is a division.

During the operation of the refrigerating unit described above, gaseous refrigerant is compressed and supplied to the condenser 14 where it is cooled and liquefied; the liquid refrigerant under control of the float valve is admitted to the manifold 41 from the liquid line 19 and flows through the manifold and into the passages 38 through the ducts 42. Some of the liquid refrigerant is vaporized because of the reduction of pressure on passing through the valve. The injection of liquid and gaseous refrigerant through the ducts 42 induces a rapid circulation of refrigerant from the passages 39 to the passages 38 through the cross passages 40, refrigerant flowing to the headers 33, 34 and 35 where the gaseous refrigerant is collected and removed through the suction line 20 and is returned to the compressor within the casing 13.

In order to obtain maximum use of the surface of the evaporator, the unit is preferably arranged within the refrigerator cabinet so that it is spaced from the side and back walls of the compartment to be cooled and so that air may circulate freely over all sides of the evaporator. The large cooling area thus provided makes it possible to operate the evaporator compartment at much higher temperatures than are necessary when a small evaporator surface is employed. The arrangement of the passages in the walls of the cooling unit illustrated is such that liquid refrigerant may be circulated effectively and thereby facilitate the maintaining of even temperatures by operation of the automatic control even though the refrigerant is in direct contact with a relatively small area of the evaporator surface.

While I have shown a particular embodiment of my invention in connection with a household refrigerating machine, other modifications will readily be apparent to those skilled in the art. I do not, therefore, desire my invention to be limited to the construction shown and described, and I intend in the appended claims to cover all modifications within the spirit and scope of my invention.

What I claim as new and desire to secure by Letters Patent of the United States is:

1. A flooded evaporator for refrigerating machines comprising a substantially vertical wall having formed therein a header and two upright passages communicating therewith and depending therefrom and a plurality of transverse passages connecting said upright passages for circulating refrigerant in said wall, each of said transverse passages communicating with one of said upright passages at a higher point than with the other of said upright passages, means for supplying refrigerant to said passages and for withdrawing refrigerant from said header, said supplying means including means for injecting refrigerant upwardly into said one of said upright passages for producing a circulation of refrigerant through said transverse passages from the other of said upright passages to said one upright passage. 5
2. A flooded evaporator for refrigerating machines including complementary metal sheets secured together to form an upwardly extending wall, a refrigerant header formed between said sheets near the upper end thereof, a pair of substantially parallel passages extending from said header and formed in one of said sheets, means including a plurality of transverse passages formed in the other of said sheets for connecting said first-mentioned passages, said transverse passages being inclined upwardly from one of said parallel passages to the other of said parallel passages, an inlet connection for admitting liquid refrigerant to said passages, and an outlet connection for removing gaseous refrigerant from said header. 10
3. A flooded evaporator for refrigerating machines including complementary metal sheets secured together to form an upwardly extending wall, a refrigerant header formed between said sheets near the upper end thereof, a pair of substantially parallel passages extending from said header and formed in one of said sheets, a plurality of transverse passages formed in the other of said sheets for connecting said first-mentioned passages, means including an inlet connection for injecting liquid refrigerant upwardly into one of said parallel passages to produce a circulation of refrigerant through said transverse passages from the other of said parallel passages to said one parallel passage, and an outlet connection for removing gaseous refrigerant from said header. 15
4. A flooded evaporator for refrigerating machines including a substantially vertical wall comprising two complementary metal sheets, means including a header formed between said sheets with two upright passages communicating therewith and depending therefrom and a plurality of transverse passages connecting said upright pas- 20
5. A flooded evaporator for refrigerating machines including a substantially vertical wall comprising two complementary metal sheets, means including a header formed between said sheets and two upright passages communicating therewith and depending therefrom and a plurality of transverse passages connecting said upright passages for circulating refrigerant in said wall, said upright passages being formed in one of said sheets and said transverse passages in the other of said sheets, means for supplying liquid refrigerant to said passages and for withdrawing gaseous refrigerant from said header, each of said transverse passages communicating with one of said upright passages at a higher point than with the other of said upright passages, and means injecting refrigerant upwardly into said one of said upright passages for producing a circulation of refrigerant through said transverse passages from the other of said upright passages to said one upright passage. 25
6. A flooded evaporator for refrigerating machines comprising a plurality of substantially vertical walls, each of said walls having a header formed near the top thereof and two upright passages communicating therewith and depending therefrom and a plurality of transverse passages connecting said upright passages, means for supplying refrigerant to said passages and for withdrawing refrigerant from one of said headers, means providing communication between said headers, each of said transverse passages in each of said walls communicating with one of the upright passages in said wall at a higher point than with the other of said upright passages in said wall, and means injecting refrigerant upwardly into said one of said upright passages in each of said walls for producing a circulation of refrigerant through said transverse passages, said refrigerant injecting means including a manifold arranged substantially parallel to said transverse passages. 30
